UNITED STATES PATENT OFFICE.

JOHN A. HALL, OF EAST ORANGE, NEW JERSEY, ASSIGNOR TO WESTERN ELECTRIC COMPANY, INCORPORATED, OF NEW YORK, N. Y., A CORPORATION OF NEW YORK.

CALLING DEVICE.

1,387,314.

Specification of Letters Patent. Patented Apr. 20, 1920.

Application filed July 12, 1917. Serial No. 180,162.

To all whom it may concern:

Be it known that I, JOHN A. HALL, a citizen of the United States, residing at East Orange, in the county of Essex and State of New Jersey, have invented certain new and useful Improvements in Calling Devices, of which the following is a full, clear, concise, and exact description.

This invention relates to calling devices of the type used in telephone systems, wherein the subscriber sets up a connection with a called substation without the help of an operator.

In certain telephone systems, such, for instance, as that disclosed in patent to Clausen, April 16, 1918, No. 1,262,752, one or more series of keys are used for controlling relays, which establish a desired connection. In such systems it is the practice to 20 actuate first, a so-called tens key, and then a so-called units key, whereupon a tens relay and a units relay will respond and establish a talking path between the calling and called substations. The use of separate keys in this manner, however, is objectionable in a commercial system by reason of the space required and the unsightly appearance presented.

The object of the present invention is to 30 provide a calling device for use in a system of the kind mentioned, which is similar in appearance and manipulation to the well known commercial automatic telephone dial switch of the present day.

It is thought that the invention will be best understood through the following detailed description and drawings, in which Figure 1 is a front view of the calling device, partly in section; Fig. 2 is sectional 40 side view of the same; Fig. 3 is a detail of the mechanism by which the calling device, after manipulation, may be restored to its normal condition; Fig. 4 is a perspective view showing the calling device attached to 45 a desk stand, and the manner in which the restoring mechanism of Fig. 3 is controlled by the switchhook; and Fig. 5 is a diagrammatic representation of the effective circuit set up through the use of such calling device.

This calling device is particularly applicable to the system described in the patent to Clausen hereinbefore referred to, wherein mechanically locking relays are employed 55 to perform functions similar to the tens

and units relays of the before mentioned patent. In the operation of this calling device the finger is placed in the proper finger hold and the dial rotated until the finger comes up against a stop, when it is withdrawn to allow the dial to return to normal, as in the well known present day calling devices. The rotation of the dial in this case, however, moves a wiper over a series of contacts, but does not electrically affect them until the finger stop is engaged. This stop, unlike that on the ordinary calling device, has a slight movement through which a momentary electrical change is effected in the circuit connected to that contact upon which the wiper rests. In this manner the contacts are selectively affected.

In the preferred arrangement shown in the drawings, the switch is built up on a frame F. Journaled in this frame is a shaft S to which is rigidly attached a dial D having the usual number of finger holds.

There are provided two wipers W¹ and W² rigidly attached to, but insulated from, the shaft S. Two series of contacts, 0 to 9, inclusive, and 10 to 19, inclusive, are arranged in a circle around the shaft S in operative relation with the wipers W¹ and W², respectively. The rotation of the dial then causes the wiper W¹ to successively engage the contacts 0 to 9, and the wiper W², the contacts 10 to 19.

There are also provided two springs S¹ and S² rigidly attached to, but insulated from, the frame F, which make sliding contact with the wipers W¹ and W², respectively, being always in connection with the same. These springs are so fashioned that their ends form terminals 20 and 21, with which a wiper W³ coöperates. The wiper W³ is rigidly attached to, but insulated from, a collar C, mounted on a shaft S³, also journaled in the frame F.

The shaft S³ carries, at its upper end, the finger stop 22, and is rotated through the movement of such finger stop.

There is an arm 23, carrying a pawl 24, also rigidly attached to the shaft S³. A ratchet wheel 25 is rigidly mounted on the collar C and thereby rigidly attached to the wiper W³. Through the agency of pawl 24, the ratchet wheel 25 may be rotated and retained in its position by a holding pawl 26.

The first encounter of the finger with the finger stop 22 serves to rotate the wiper W³.

over and beyond the terminal 20 so as to make a passing contact therewith. The second encounter of the finger with the stop 22 in a like manner rotates the wiper W^3 over 5 and beyond the terminal 21 so as to make a passing contact therewith.

Connected to the frame F are levers L^1 and L^2 with a link L^3 connecting the two. This link L^3 carries projections 27 and 28, 10 which coöperate with fingers 29 and 30, which are integral parts of the pawls 24 and 26, respectively. The lever L^1 is connected by a rod 31 with the switchhook in a suitable manner, so that, when the receiver 15 is removed from its hook, the consequent movement of the levers L^1 and L^2 , and the connecting link L^3 is such as to allow the pawls 24 and 26 to engage the ratchet wheel 25. The replacing of the receiver on its 20 hook moves the connecting link in such a manner that the projections 27 and 28 engage the fingers 29 and 30 so as to remove the pawls 24 and 26 from engagement with the ratchet wheel 25 and allow it to return, 25 under the tension of a spring 32, to its normal position.

Rigidly attached to the shaft S is a gear wheel G^1 , which meshes with the gear wheel G^2 , attached to a governing device G, to 30 properly control the movement of the dial D and its attached members.

When the dial D is moved the wipers W^1 and W^2 successively pass over the contacts 0 to 9, and 10 to 19, inclusive, respectively, 35 and, as the finger engages the stop 22, the wipers come to rest, each on one of its associated contacts. At this time the wiper W^3 passes over the terminal 20 so that a momentary circuit is established in a manner 40 to be more fully described hereinafter. As the finger is removed from the finger hold, the shaft S and its associated members are returned to normal through the agency of a coiled spring 33.

45 A calling device, such as has been described, is of use in the circuit shown in Fig. 5, where each one of the contacts, 0 to 9, and 10 to 19, inclusive, is connected to relays, such as the before mentioned tens and 50 units relays. The wiper W^3 is connected to ground, so that, during its passage over the terminal 20, a circuit is established from ground, wiper W^3 , terminal 20, wiper W^1 , its then engaged contact in the series of 55 contacts 0 to 9, the relay R connected therewith, to battery and ground. The relay R may be locked up in any suitable manner. The wipers W^1 and W^2 are now returned to normal through the agency of the spring 60 33, and, upon the second manipulation of the dial, when the finger comes in engagement with the stop 22, the wiper W^3 is moved over the terminal 21, whereupon a circuit is momentarily established from

then engaged contact in the series 10 to 19, inclusive, a relay connected therewith, to battery and ground.

What is claimed is:

1. In a calling device, sets of contacts, 70 wipers arranged in operative relation therewith, a dial provided with finger holds for actuating said wipers, and means responsive to the angular movement of said dial for momentarily selectively affecting said 75 contacts.

2. In a calling device, sets of contacts, a wiper arranged in operative relation with each of said sets of contacts, a rotatably mounted dial provided with finger holds for 80 actuating said wipers, and means responsive to movement of said dial for selectively and successively establishing a transient circuit through said wipers.

3. In a calling device, sets of contacts, a 85 wiper arranged in operative relation with each of said sets of contacts, a rotatably mounted dial provided with finger holds for actuating said wipers, a finger stop, and means responsive to the engagement of said 90 finger stop and movement of said dial for selectively affecting said contacts.

4. In a calling device, sets of contacts, a wiper arranged in operative relation with each of said sets of contacts, a rotatably 95 mounted dial provided with finger holds for actuating said wipers, a finger stop, and means controlled by said finger stop for successively establishing a circuit through said wipers.

5. In a calling device sets of contacts, a wiper arranged in operative relation with each of said sets of contacts, a rotatably mounted dial provided with finger holds for actuating said wipers, a finger stop, means 105 responsive to the engagement of said finger stop for successively establishing a circuit through said wipers, and means responsive to the movement of said dial for selectively affecting said contacts.

6. In a calling device, sets of contacts, a wiper arranged in operative relation with each of said sets of contacts, a movable dial provided with finger holds for causing the wipers to move over said contacts to selectively engage any one thereof, and means operated by the movement of said dial and after a selected contact has been engaged for momentarily establishing a circuit there-through.

7. In a calling device, sets of contacts, a wiper arranged in operative relation with each of said sets of contacts, a rotatably mounted dial provided with finger holds for actuating said wipers, and means for limiting the motion of said dial and for momentarily closing a normally open circuit through said wipers.

8. In a telephone system, sets of relays.

- ing said relays comprising means for momentarily energizing a relay of a different set upon each manipulation of said device.
9. In a telephone system, sets of relays, and a rotatable calling device for selectively operating said relays comprising means for momentarily energizing a relay of a different set upon each manipulation of said device.
10. In a telephone system, sets of relays, and a finger wheel calling device for selectively operating said relays comprising means for momentarily energizing a relay of a different set upon each manipulation of said device.
11. In a telephone system, sets of relays and a calling device for selectively operating said relays, said device comprising sets of contacts connected to said relays, a wiper, and means for transiently establishing a circuit including said wiper, a selected contact and a relay connected thereto.
12. In a telephone system sets of relays, and a calling device for selectively operating said relays, said device comprising sets of contacts individual to said sets of relays, a wiper, and means for transiently establishing a circuit through said wiper including a selected contact and a relay connected thereto in one of said sets, and means for subsequently establishing a circuit through said wiper including a selected contact and a relay connected thereto in another of said sets.
13. In a telephone system, series of relays, a calling device for actuating said relays, means included in said calling device to select and operate a relay of one of said series upon one actuation of said calling device, and means to select and operate a relay in another of said series upon a subsequent actuation of said calling device.
14. In a telephone system, series of relays, a calling device for actuating said relays, sets of contacts in said calling device individual to said sets of relays, means included in said calling device for transiently establishing a circuit through a selected contact in one of said sets of contacts, and means included in said calling device for transiently establishing a circuit through a selected contact in another of said sets of contacts.

In witness whereof, I hereunto subscribe my name this 10th day of July, A. D. 1917.

JOHN A. HALL.
